UNITED STATES PATENT OFFICE.

GRANVILLE S. P. HOLLAND, JR., OF NORFOLK, VIRGINIA.

TESTING DEVICE FOR SPARK-PLUGS.

1,395,570.

Specification of Letters Patent.

Patented Nov. 1, 1921.

Application filed April 6, 1920. Serial No. 371,613.

To all whom it may concern:

Be it known that I, GRANVILLE S. P. HOLLAND, Jr., a citizen of the United States, residing at Norfolk, in the county of Norfolk and State of Virginia, have invented certain new and useful Improvements in Testing Devices for Spark-Plugs, of which the following is a specification.

My invention relates to devices for short circuiting the spark plugs of internal combustion engines, for the purpose of testing the action of the plug or plugs which remain in operation.

The particular object of the invention is to provide a short circuiting device which is of simple, cheap and durable construction, and which may be very easily and quickly placed on the spark plugs and removed, in the testing operation.

The accompanying drawing shows one modification of the invention. After considering this in connection with the accompanying description, persons skilled in the art will understand that variations may be made without departing from the principles of the invention, and I do not limit myself to details, except as claimed.

Figure 1 is a side elevation of the device applied to a spark plug in position on an engine cylinder.

Fig. 2 is a top plan of the device removed from the plug, and

Fig. 3 is a vertical section.

The invention in the preferred form comprises a metallic conductor or contact member 1, and a clip 2, a handle 3, and means such as a screw 4, for securing the handle to the conductor and clip.

Usually, as shown, the conductor and clip are formed of a single piece of sheet metal of moderate thickness. This may be any suitable metal or alloy, but may preferably be of spring sheet steel. The conductor or connector 1, usually has its upper part 5 relatively short and curved away from the handle at a point near its end 6, and provided with a recess or cavity 7. The lower part 8 of the conductor is usually relatively longer and this part is usually slightly curved in a direction away from the handle as shown.

The clip 2 comprises two arms, 9 and 10, extending from the conductor 1. Each of these arms has a curved portion 11, forming, together, a space 12 adapted to receive the insulator or porcelain of the spark plug, and

outwardly from the curved portion 11, each arm has another curved portion 13, terminating in ends 14, which are outwardly flared.

The handle 3 may be of any suitable insulating material, such as wood, and may be conveniently secured to the metal portion of the device by a screw 4, or in any other suitable way.

The clip 2 is adapted to be quickly snapped or sprung over the porcelain insulator of any standard spark plug, by merely pushing the flared ends of the clip against the porcelain. The clip then immediately seizes the porcelain with a firm spring pressure and holds the end 7 of the conductor 1 against the metal terminal "T" of the plug, and holds the lower end of the part 8 of the connector against the nut "N," which constitutes a part of the body of the plug. The construction of the clip and connector are such that one size of the device easily accommodates not only spark plug porcelains of greatly varying diameter, but the connector adapts itself to great variations in the distance between the nut or body of the spark plug and the metallic terminal members at the top of the plug.

It is obvious, without further description, how the testing device may be quickly placed on a plug to short circuit it, and quickly removed and placed on another plug. Evidently by providing a plurality of the short circuiting devices, say three for a four cylinder engine, any one or more of the plugs may be short circuited at the same time, to test the action of the remaining plug or plugs and by shifting the devices from one plug to another, any plug which is performing improperly may be quickly detected.

Having thus described my invention, what I claim is:

1. A short circuiting device for spark plugs, comprising a metallic conductor 100 adapted to engage the upper terminal and the body of a spark plug, a spring clip located intermediate the ends of the conductor and adapted to embrace the insulating portion of the plug, between the terminal and 105 the body, and a handle of insulating material.

2. A short circuiting device for spark plugs, comprising a relatively long conductor having its upper end adapted to engage 110 the terminal of a spark plug and its lower end adapted to engage the body of the plug,

regardless of considerable variation in the distance between said terminal and body, a spring clip consisting of two arms extending from the conductor and adapted to embrace the porcelain of the spark plug, regardless of considerable variation in the diameter of the porcelain, and a handle of insulating material joined to the conductor.

3. A short circuiting device for spark plugs, comprising a metallic body of spring sheet metal including a relatively long conductor having a curved and recessed upper end, adapted to engage the terminal of a spark plug, and a lower end adapted to engage the body of the plug, regardless of considerable variation in the distance be-

tween the terminal and the body, and also including a spring clip consisting of two arms extending from the sides of the conductor and bent inwardly and then outwardly providing flaring ends, and adapted to embrace the porcelain of a spark plug, a handle of insulating material and a screw connecting the handle to the metallic body of the device at a point near the intersection of the conductor and the clip.

In testimony whereof I affix my signature in presence of two witnesses.

GRANVILLE S. P. HOLLAND, JR.
